Primary Examiner — Marie D. Fast Horse(74) *Attorney, Agent, or Firm* — Patterson + Sheridan, LLP(57) **CLAIM**

The ornamental design for a payment reader cradle, as shown and described.

DESCRIPTION

FIG. 1 is a perspective view of a payment reader cradle showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The portions of the payment reader cradle shown in broken line form no part of the claimed design.
